UNITED STATES PATENT OFFICE.

WILLIAM PATON THOMSON, OF NEW YORK, N. Y., ASSIGNOR TO THE RAIL JOINT COMPANY, OF NEW YORK, N. Y., A CORPORATION OF NEW YORK.

RAIL-JOINT.

1,314,767.

Specification of Letters Patent.

Patented Sept. 2, 1919.

Application filed June 6, 1918. Serial No. 238,516.

To all whom it may concern:

Be it known that I, WILLIAM PATON THOMSON, citizen of the United States, residing at New York city, in the county of 5 New York and State of New York, have invented certain new and useful Improvements in Rail-Joints, of which the following is a specification.

This invention relates to an improvement 10 in rail joints of the continuous type.

Primarily, the invention contemplates a 15 novel formation of foot flange for the bar to provide adequate pliancy to insure greater facility of application in track and an accurate fit to the underside of the rail base. To this end, the improved structure is so 20 designed that the rail supporting base member may be seated in a more horizontal manner than is generally possible where the construction of the lower portion of the bar is 25 such as to involve a substantial hinging action in the metal at the junction between the foot and the rail supporting base member, or where such hinging action is focused 30 or concentrated at any other single point. It is therefore, one of the important objects 35 of the invention to provide the desired pliancy in the lower part of the joint bar without focusing breaking strains in a restricted 40 location or area, while at the same time so distributing the metal in the lower part of 45 the bar, in relation to the horizontal neutral axis, as to obtain a distinct structural improvement from a standpoint of resistance 50 to bending of the bar in undesirable locations, and also from the standpoint of increasing the efficiency of a given amount of metal in the bar. By reason of taking these 55 important structural factors into consideration 60 it is possible, according to the present invention, to design a continuous joint bar having adequate pliancy in the foot member 65 to insure a proper fit of the bar on the rail flange under all conditions, as well as a 70 proper seating of the base member of the bar 75 in substantially a horizontal plane without focusing abnormal strains at any one point or location.

With the above and other objects in view 80 which will more readily appear as the nature 85 of the invention is better understood, the same consists in the novel construction, combination and arrangement of parts herein- 90 after more fully described, illustrated and 95 claimed.

A preferred and practical embodiment of the invention is shown in the accompanying drawings, wherein:

The figure is a diagrammatic end elevation 60 illustrating a rail of standard section having applied thereto a continuous joint bar embodying the present features of improvement.

As indicated, the present invention is 65 chiefly directed to an improvement in the base portion of a continuous type joint bar which includes the upper inclined foot member 1 and the horizontal rail base supporting member 2 connected by an integral neck portion 3. In carrying the invention into effect 70 it is proposed to form a foot member 1 of substantially uniform thickness, preferably from the point where the arc of the fillet *a* at the lower end of the bar-web terminates 75 in the inclined upper face of the foot flange, to a point where the arc of the fillet *b* at the neck 3 merges into the under face of the foot flange. This construction in effect produces within the foot member of the bar a 80 well defined attenuated section *x* of a substantial length and area as distinguished from a restricted location or point, as for instance at the junction between the foot and the web of the bar or at the junction of the foot and base member of the bar.

The said section *x* may be, and preferably 85 is, of a less thickness than the bar foot member found in common practice, and has a well defined clearance, as indicated at 4, 90 from the upper side of the rail flange. These features accentuate the function of the said section *x* as a flexing web-section which assures an adequate pliancy, permitting the foot member to readily spring downwardly 95 from the said section *x* when the bar is being fitted upon the rail flange. This spring action is coextensive with the length of the attenuated web section *x*, and, being distributed over a considerable area, necessarily 100 obviates the objection which exists to focusing or concentrating the flexing of the lower portion of the continuous joint bar in a restricted location, area, or neck.

In the process of rolling the novel section herein described, it is preferable to distribute the metal in such a manner that the connecting neck 3 between the foot 1 and the base 2 is of a greater thickness than is customary, and also whereby the width of said neck, as indicated at 105 *y*, will be sub- 110

stantially greater than the thickness of the flexing web section α . This prevents a hinging action in the said neck 3 as has been the case in former structures, and compels the said spring or flexing action to be confined to the section α . And, furthermore, the increased thickness of the neck 3 provides a substantial mauling shoulder for driving the joint bar onto the rail flange.

To assist in confining the flexing or spring action of the bar to and within the flexing web section α a preferable detail which may be observed in the designing of the bar is to have the clearance 5, for the base flange of the rail, materially increased over the common practice, thus further augmenting the resilient effect of the foot flange 1. In this connection it is to be noted that a distinctive feature of the present invention is to have the elongated flexing section α extend beyond the vertical plane of the outer edge of the rail flange and coöperate with the clearances between the joint bar and the outer and under edge portions of the rail flange as clearly shown in the figure of the drawings. By reason of having these ample clearances beyond and beneath the edge of the rail flange the elongated and attenuated flexing section α becomes quite effective as a spring section adapting itself to an accurate fit of the bar to the joint bar upon and beneath the rail flange for its intended purpose.

A further feature of the invention resides in the special formation of the inner lower corner portion of the foot flange 2 within the zone covered by the dotted lines c . That is to say, by beveling or truncating the inner end of the foot flange 2 of the bar, as shown, the tie resistance due to forcing the bar inward toward the rail web is reduced to a minimum, and at the same time some metal is saved which may be advantageously used elsewhere in the bar to improve the structural strength thereof.

It will thus be seen that a distinctive and important phase of the invention is that of providing a structure distinguishing from bars of those types wherein a hinging action occurs in the lower portion of the bar at some restricted location or area, usually a contracted neck. To that end the distinctive and practical result of the improved construction is that of providing an adequate pliancy in the foot of the splice bar, thus permitting the base part of the bar to open and adapt itself to a tapering rail flange without focusing or concentrating strains in any restricted or contracted point. This insures a facile application in track, a more accurate fit of the base of the bar to the under side of the rail, and entirely obviates any tendency of the base member of the bar to move away

from the bottom of the rail either in a downwardly and outwardly direction, or in a downwardly and inwardly direction. Furthermore, it will now have been observed that another desirable feature incident to the lengthening of the attenuated web section α is that the angularity of the straight body of metal in the foot is flattened, as distinguished from the usual tapered effect, thereby better resisting loading thrusts at a greater distance on the tie from the vertical center line of the rail than ordinarily.

From the foregoing it is believed that the construction and advantages of the herein described improvement will be apparent to those familiar with the art without further description and it will be understood that changes in the form, proportion and minor details of construction may be resorted to without departing from the spirit of the invention or the scope of the appended claims.

I claim:

1. A rail joint bar including a base member, and a foot member having a flexing section overlying the rail flange and extending beyond the edge thereof. 90

2. A rail joint bar including a base member, and a foot member having an attenuated flexing section overlying the rail flange and extending beyond the edge thereof. 95

3. A rail joint bar including a base member, and a foot member connecting with the base member to provide a clearance beyond the edge of the rail flange and formed with an attenuated flexing section disposed above the rail flange. 100

4. A rail joint bar including a base member, and a foot member connecting with the base member to provide a clearance beyond the edge of the rail flange and formed with an attenuated flexing section disposed above the rail flange and extending substantially beyond the same. 105

5. A rail joint bar including a base member and a foot member connecting with the base member to provide clearance beyond and beneath the edge of the rail flange, said foot member having a flexing section overlying the rail flange and extending beyond the edge thereof. 115

6. A rail joint bar including a base member and a foot member connecting with the base member to provide clearance beyond and beneath the edge of the rail flange, said foot member having an attenuated flexing section overlying the rail flange and extending beyond the edge thereof. 120

7. A rail base-supporting joint bar having a foot member provided with a flexing section of substantially uniform thickness throughout, said flexing section being of a length to in part overlie the rail flange and in part extend beyond the edge of the same. 125

8. A rail base-supporting joint bar hav-

ing a foot member provided with an attenuated flexing section of substantially uniform thickness throughout and formed to provide a clearance from the upper side and 5 outer edge portion of the rail flange.

9. A rail joint bar including a base member and a foot member having a neck connection with a base member to provide a clearance beyond the edge of the rail flange, 10 said foot member being provided with a flexing section of less thickness than said connecting neck.

10. A rail joint bar including a base member and a foot member having a neck connection with a base member to provide a clearance beyond the edge of the rail flange, 15 said foot member being provided with an attenuated flexing section of less thickness than said connecting neck.

11. A rail joint bar including a base member and a foot member having a flexing web section overlying the rail flange and extending beyond the edge thereof, said flexing web section occupying substantially the area between the neck connecting the foot with 20 the bar and the neck connecting the foot with the base member.

12. A rail base-supporting joint bar having a foot member provided with a flexing section spaced above the rail flange and 25 extending substantially beyond the edge thereof.

In testimony whereof I hereunto affix my signature in the presence of two witnesses.

WILLIAM PATON THOMSON.
